HEEL GLUING MACHINE

Walter A. Thum, St. Louis, Mo.

Application March 20, 1942, Serial No. 435,533

26 Claims. (Cl. 12—80)

My invention relates generally to shoe machinery and has more particular reference to a machine for the application of glue to the cup of a shoe-heel.

The shoe heels which my invention is intended to work upon are made with a cup or hollowed out portion to fit the contour of the heel-seat of the shoe to which the heel is to be glued in the process of making the shoe. This cup or recess, which is relatively shallow, opens at full depth at the front or breast of the heel but thins out to the side and rear edges or arc of the heel. Making an effective junction of the heel with the shoe, it is desirable that the cup should be glued uniformly over its central area, while leaving a margin of the arc of the heel free of the glue for preventing extrusion of the glue in an unsightly manner when the heel and the shoe are clamped together. With the foregoing in mind, my invention has for one of its objects the provision of a machine for the application of glue to the cup of a shoe-heel, wherein a film of the glue covers the central portion of the heel-cup, while leaving a narrow band or margin of unglued surface around the arc of the cup of the heel.

It will also be readily seen that a mere wiping process for the gluing operation is quite impracticable if such a glue-free margin is to be maintained around the arc of the heel, more especially along the rear side thereof. My invention, therefore, has for a further object the provision of a machine for the application of glue to the cup of a shoe-heel wherein the side and rear margins of the cup are masked, and the glue is printed, not wiped, through the mask onto the central unmasked portion of the cup of the heel.

And with the above and other objects in view, my invention resides in the new and novel features of form, construction, arrangement, and combination of parts hereinafter described and more particularly pointed out in the claims.

In the accompanying drawings (three sheets),

Figure 1 is a side elevational view of one form of a heel-gluing machine embodying my invention;

Figure 2 is an enlarged fragmentary detail view taken approximately along the line 2—2 of Figure 9;

Figure 3 is a top plan view of a heel showing the heel-cup with a film of glue applied thereto according to my invention;

Figure 4 is a top plan view of the machine, the housing being removed and other parts broken away, the several parts being shown in normal or initial heel-receptive position;

Figure 5 is a fragmentary detail sectional view taken approximately along the line 5—5 of Figure 4;

Figure 6 is a side elevational view of the machine with the housing in place, parts thereof being shown broken away and other parts in section;

Figure 7 is a sectional view taken approximately along the line 7—7 of Figure 6, but showing the several parts of the machine in positions corresponding to Figure 8;

Figure 7a is a fragmentary view with the heel-rest in its elevated position between the arms, said heel-rest being in horizontal alignment with the bight of the grooves;

Figure 8 is an enlarged fragmentary detailed sectional view, showing the carriage in lowered position with the closed end of the cup of a supported heel in glue-printing engagement with the glue transfer roller, other parts of the machine being broken away;

Figure 9 is a top plan view of the machine illustrating the heel with the masking and supporting means locked around the periphery thereof;

Figure 10 is a side elevational view of the machine with the housing in place and partly broken away for disclosing the lock in retracted or released position; and

Figure 11 is a fragmentary sectional view, illustrating the carriage during movement to its elevated position.

Preliminary to a description of the machine, attention is directed to Figure 3, which, as will be understood by those skilled in the art, is an illustration, or top plan view, of the hollowed-out cup *a* of a heel *H*. The rear side or closed end of the cup *a* is bounded by the raised lip or arc *e*, *f*, *g*, of the heel *H*, while the front side or open end of the cup *a* is bounded by a raised lip on merely its two sides *e*, *g*, the hollow of the cup being cut through the front face *h* of the heel. In accordance with my invention, a film of glue *b* is shown applied to the heel *H* in such a manner as to provide a glue-free margin *c* between the glue *b* and the arc *e*, *f*, *g*, of the heel-cup *a*.

Referring now more in detail and by reference characters to the drawings, which illustrate a preferred embodiment of my invention, the machine, generally designated *A*, includes a base *1* mounted, as by clamps *2*, on the respective horizontal portions *3* of a pair of laterally spaced floor stands whose respective vertical members or legs *4* have floor flanges *5* for engaging a floor, as *6*.

A foot pedal *7* is fulcrumed, as at *8*, on one of

the legs 4' of the stand, and has a link connection 9 with a crank 10 mounted on a shaft 11 journaled in bearings 12 mounted on the horizontal portions 3 of the stand. The shaft 11 is disposed transversely in front of the machine A and carries a downwardly presented arm 13, from which is suspended a counterweight 14, and an upwardly presented arm 15 to which is pivoted a link or pitman 16 adapted normally to extend rearwardly from the arm 15 over the machine A.

Around the periphery of the base 1 of the machine A, is suitably seated a rubber sealing strip 17 adapted to be normally engaged in turn by the continuous bottom face, as 18, of the respective side and end walls of a machine housing or inverted box-like cover 19. Adjacent the bottom margin of the rear end wall of the cover 19, is a lug 20 adapted for engagement by a hook 21 on the base 1, and adjacent the bottom margin of the front end wall of the cover 19, is another lug 22 adapted for engagement by a clamp 23 pivoted on the base 1, whereby the cover 19 may be compressibly, though removably, mounted on the base 1 in sealing engagement with the rubber strip 17, as best seen in Figures 1 and 7.

In its top wall, the cover 19 is provided with an aperture 24, and around the aperture 24 is likewise suitably seated a rubber sealing strip 25 adapted to be engaged by a lid 26 hingedly supported, as at 27, on the cover 19; the cover 19 has a back-stop 28 which supports the lid 26 in its open position. Hinged on the frontal top side of the cover 19, is a clamp 29 for engaging a lug (not shown) on the lid 26, whereby the same may be compressibly, though removably, engaged sealingly on the rubber strip 25 for closure of the aperture 24 subsequent to removal or swinging back of the pitman 16, as occurs when the machine is not in use.

Preferably formed integrally with the machine base 1, is a glue basin B having spaced parallel side walls 30 and end walls 31. One of the side walls has a spout 32 through which a supply of suitable liquid adhesive or glue 33 is introduced into the basin B when preparing the machine for use, as best seen in Figures 6 and 7.

Mounted on each of the basin side walls 30, as best seen in Figure 7, is a side frame 34, and, in turn, mounted on the side frames 34 are respective parallel channel-shaped side frames or rails 35, 36; the rail 35 only has on its upper flange or side 37 a stop 38, as best seen in Figures 2 and 4, for a purpose presently appearing.

A front cross-member 39 connects the side rails 35, 36, and forms a front closure or stop 40 for the respective channels or ways 41 of the said side frames 35, 36; also connecting the rear ends of the side-rails 35, 36, is a cross member 42 forming rear closure-stops 43 for the respective ways 41. The member 42 carries a forwardly projecting platform 44 located in a central position between the rails 35, 36, for a purpose presently appearing and as best seen in Figure 4.

Intermediate its ends, the top flange 37 of each of the respective side rails 35, 36, is provided with a slot or cut-out 45, and near its rear end each flange 37 is provided with a pair of spaced slots 46, 47, with a flange-portion or shelf 48 therebetween, all of said slots 45, 46, 47, communicating the top side of the flange 37 with the way 41 therebelow.

Mounted adjacent the forward margin of the rearmost slot 47, is a swingable member or dog 49 carried by a pintle 50 fulcrumed through the

adjacent side wall of the rail 35 or 36, as the case may be, and biased by means of a suitable torsional member or spring 51 for causing the dog 49 to normally incline or depend obliquely rearwardly through the slot 47 into engagement with the floor of the way 41. Upstanding from each of the rails 35, 36, is an ear 52 carrying a pintle 53, on which is swingably mounted another dog or flap-member 54 adapted to have its free end normally rest on the shelf 48 in substantial alignment with the rear margin of the slot 46. The ear 52 carries a lateral stop 55 designed to limit the upward swing of the dog 54, all as best seen in Figures 4 and 6.

C designates a reciprocable carriage having a frame which includes laterally spaced side bars 56, 56', connected, preferably integrally, by a rear cross-bar 57. Upstanding from the inner margin of each side bar 56, 56', is a rib 58, and mounted on the ribs 58 near the front of the carriage C, is a transverse bridge or cross-bar 59. Each side bar 56, 56', has a depending lug 60 adjacent its front end; each lug 60 carries an axle 61 on which is journaled a roller 62; at its rear end, each side bar 56, 56', also has a depending lug 63, and through the pair of lugs 63 extends a single axle 64, on the projecting ends of which are journaled respective rollers 65. Each respective pair of rollers 62, 65, on a side 30 of the carriage C is adapted to work in the adjacent way 41, whereby the carriage C is supported for longitudinal movement parallel with and between the rails 35, 36.

Attached, preferably integrally, to the center 35 of the rear cross-bar 57 of the carriage C is a pintle block 66, and upstanding from the cross-bar 57 in front of the pintle block 66 is a pair of spaced pintles 67. The pintles 67 swingably support a pair of arcuate so-called clasping arms 68, the block 66 being suitably recessed to receive the hubs of the arms 68, a cover-plate 69 being removably attached to the block 66 for retaining the arms 68 on the pintles 67. The free ends 70 of the arms 68 extend forwardly into the space 30 between the carriage side bars 56, 56', each arm-end 70 being provided on its inner face with a channel 71, as best seen in Figure 7a.

A flexible and elastic U-shaped member, hereinafter referred to as the work-support D, and composed of resilient material, as rubber or the like, has its respective free ends mounted in the also respective channels 71 of the clasping arms 68; the bight d' of the work-support D is anchored to the pintle block 66 by being engaged between a hook 72 on the block 66 and another hook 72' on the cover-plate 69, as best seen in Figure 8. As will presently more fully appear, the bight d' forms a so-called rear rest for disposing the work or heel H in a defined position on the carriage C.

Provided on the inside face of the member D is a longitudinally continuous V-shaped groove 73 adapted to receive the heel-edge or arc e, f, g, of the heel H. The lower wall of the groove 73 is formed by a coextensive rib or masking member d, as best seen in Figures 7a and 7. As will presently more fully appear, the member D is adapted to embrace the arc e, f, g, responsive to heel-clasping movement of the arms 68, whereby the heel H is gripped or supported by and between the V-shaped walls of the groove 73, while concurrently therewith the rib d is extended inwardly from the arc of the heel so as to mask the margin c of the heel-cup a.

E designates a slide or wedge-operator, which

includes a cross-head 74 disposed transversely on and at the rear of the carriage C, and a pair of spaced cams or wedge-members 75, attached to the cross-head 74 and projecting forwardly therefrom, one wedge 75 being disposed on each side of the pintle-block 66, the inclined face of each wedge 75 being opposed to one of the clasping arms 68, as best seen in Figure 4.

Attached to each wedge 75 is a slipper-bar 76, which extends forwardly past the adjacent arm 68 for working in a guide or recess 77 formed in the corresponding rib 58 of the carriage frame, whereby the slide E is guided for reciprocable longitudinal movement relative to the clasping arms 68, for a purpose soon appearing, and as best seen in Figures 4 and 7.

At each end of the cross-head 74 is a depending ear 78, to which is pivotally connected, as at 79, one part 80 of a tension responsive member or composite link 80-81, of which the part 81 is shiftable or extensible relatively to the part 80, although a suitable tensional member or spring 82 serves to normally bias the part 81 in retracted position relative to the part 80.

Each link 80-81 extends forwardly on the carriage C alongside a corresponding one of the ribs 58 and has pivotal connection, as at 83, with respective arms 84, 84', located at opposite ends of a crank-shaft 85 journalled in suitable bearings 86 on the bridge-piece 59 of the carriage C, the crank-shaft 85 having a crank 87 intermediate the bearings 86, which crank 87 is normally disposed in an approximately vertical position relative to the carriage C, as best seen in Figure 6.

The crank 87 is adapted to be removably engaged in a groove 88 provided in the free end or head 89 of the pitman 16; a keeper-plate 90 is removably attached to the head 89 as by a cap-screw 91 for retaining the crank 87 in the notch 88. A post 92, upstanding from the front end of the carriage C, serves as a support for the pitman-head 89, when the latter is in its normal position, as best seen in Figure 6.

Projecting laterally from the front end of the rib 58 of the side bar 56 of the carriage C is a lug 93. Slidable on the side bar 56 in the rear of the lug 93, and normally disposed in the path of swingable movement of the adjacent crank-arm, as 84, is a latch-head 94 having a stem 95 slidably mounted in a bore 96 in the lug 93 with a tensional member or spring 97 mounted on the stem 95 between the lug 93 and the head 94 for normally yieldingly biasing the head 94 in spaced relation to the lug 93, a retainer, as at 98, being provided for preventing the escape of the stem 95 from the bore 96. On the latch-head 94, is an ear 99 projecting over the adjacent side rail 35 and adapted, on rearward movement from initial position of the carriage C, to engage the stop 38 on the rail 35, for a purpose later appearing, all as will best be understood from Figures 2 and 4.

Pivotedly mounted, as at 100, on a shaft 101 extending between and supported by the main frame side-members 34, is a lever 102 having a laterally and upwardly extended arm 103 carrying a toe 104 disposed normally above the carriage side bar 56', so as to be in the path of swinging movement of the adjacent crank-arm, as 84'.

A rod or link 105, attached to the lever 102, has pivotal connection, as at 106, with a latch-lever 107 fulcrumed at its lower end on a shaft 108 which extends transversely of the machine between the side frames 34. An arm 109 of the lever 107 depends below the shaft 108 and is ten-

sionally connected, as by a spring 110, with the lever 102. The upper end of the latch-lever 107 is provided with a detent 111, as best seen in Figure 6.

5 A shaft 112, preferably journalled in suitable bearings 113 formed in the joint between the respective side rails 35, 36, and the side frames 34, extends likewise transversely of the machine above and to the rear of the lever shaft 108. F designated a so-called heel-rest lifter, which includes two cranks 114, one adjacent to each of the respective side rails 35, 36, and which are journalled on the shaft 112, from which the cranks 114 extend forwardly in the machine and are connected by a cross-beam 115 parallel with the shaft 112. Stop-brackets 116 extend inwardly from the respective side frames 34 and serve to support the beam 115 when in its lowermost position, but when the beam 115 is in its initial or upper position, it is engaged with the detent 111, whereby the lifter F is releasably supported in such position by the latch-lever 107.

Upstanding from each crank 114, is an arm 117 carrying at its upper end a lateral pin 118 adapted to work in a way 119 extending longitudinally on the under side of the adjacent one of the carriage side bars 56, 56', the ways 119 being open at their forward ends for ease in mounting the carriage C in the machine.

Upstanding from the beam 115, is a yoke 120 of an inverted U-shape, the horizontal portion or bight of the yoke 120 forming a guide rod for a pair of opposingly slidable wedge-shaped members or so-called front heel-rests 121, the small 30 ends thereof being opposed one to another on the yoke 120. At its outer end, each heel-rest 121 is provided with an inverted U-shaped extension or apron 121' which serves to shield the yoke 120 from glue and thus avoid obstructions to free movement of the rests 121 thereon. By means of an interposed spring 122, the rests 121 are suitably biased so as to follow the clasping arms 68 in their swinging movement, stops 123 serving to limit the outward travel of the heel-rests 121, 35 as best seen in Figures 7 and 7a.

Mounted on the shaft 112, is a glue-transfer or printing roll 124 of sponge-rubber or the like. The position of the printing roll 124 in the machine bears a definite relationship to the reference point d' of the carriage C when the latter is in its initial position, which relationship will more particularly be presently pointed out. It suffices here merely to say that the roll 124 is preferably spherical in shape, is very elastic, 40 and has the property of carrying a film of glue on its peripheral surface.

The roll 124 is secured at its opposite ends to respective hubs 125 mounted on and secured to the shaft 112. Each hub 125 is equipped with a ratchet-wheel or gear 126. Adjacent each hub 125, is a gear 127 journalled on the shaft 112 and carrying a pawl 128, biased by a spring 129, for co-operating with its adjacent ratchet wheel 126, as best seen in Figures 7 and 8.

Each gear 127 has toothed cooperation with a rack 130 located in a channel or recess 131 formed in the under side of the adjacent rib 58 of the corresponding side-bar 56 or 56', as the case may be, of the carriage C. Each rack 130 45 is swingably mounted at its forward end on a pin 132 mounted in the rib-walls, and the free or rearward end of the rack 130 is biased upon its co-operating gear 127 by means of a tensional member or leaf-spring 133, as best seen in Figure 5.

The shaft 112 is extended at each end through the respective bearings 113. On one so-extended end of the shaft 112 is secured a gear 134, which turns with the shaft 112 and has co-operation with a subjacent gear 135 secured to one end of a shaft 136 extending transversely between the glue basin side walls 30 and journaled in suitable bearings 137 respectively provided in the joint between the respective side basin wall 30 and the side frame walls 34.

On the shaft 136 is secured a glue-feeder roll 138 of suitable material adapted to turn with the shaft 136; the roll 138 is in registration with, and has a contour complementary to, the printing roll 124 for feeding the glue 33 from the glue basin B to the surface of the printing roll 124; the gears 134, 135, are preferably selected so as to drive the rolls 124, 138, at the same peripheral speed.

At the other extended end of the shaft 112 is a gear 139, which also turns with the shaft 112 and has co-operation with a gear 140 secured to one end of a shaft 141 which extends transversely between, and likewise freely through apertures 142 provided for the purposes in, the side frames 34, as best seen in Figure 7.

The respective extreme ends of the shaft 141 are journaled in bearings 143 provided in also respective side arms 144 of a yoke 144', each arm 144 being swingably mounted, as at 145, on the correspondingly adjacent extreme end of the shaft 112, as best seen in Figures 7 and 8. The free end of each arm 144 has an eye 146 through which works the shank of a thumb-screw or bolt 147 adjustably threaded through a bracket 148 projecting from the adjacent side frame 34. The threaded portion of the bolt 147 ends in a shoulder 149 which bears on one side of the lever eye 146. The shank of the bolt 147 is also threaded and carries a nut 150; a spring 151 is interposed between the nut 150 and the eye 146 for tensionally biasing the same against the shoulder 149, as best seen in Figure 6.

Secured to the shaft 141 for rotation therewith, is a wiper roll 152 which is located in registration with, and has a contour complementary to, the feeder roll 138, the respective gears 139, 140, being proportioned to drive the rolls 138, 152, at about the same peripheral speed. By suitably adjusting the respective bolts 147, however, the periphery of the wiper roll 152 may be spaced suitably from the periphery of the feeder roll 138 for predetermining the thickness of the film of glue on the latter and thus, in turn, regulating the quantity of glue fed from the roll 138 to the transfer roll 124, as best understood from Figure 8.

In its normal or initial position, as shown in Figures 4 and 8, the carriage C is disposed with its front rollers 62 abutting the forward stops 40 of the ways 41 in the side frame rails 35, 36; the pins 118 of the heel-rest lifter F are engaged in the grooves 119 on the under side of the carriage C, and the beam 115 is engaged in the detent 111 of the latch-lever 107, whereby the carriage C, pivoting on the front rollers 62, is tilted upwardly toward the rear with the back rollers 65 suspended at the level of the top flanges 37 of the side rails 35, 36, in registration with the notches 46 and immediately in front of the upper dogs 54.

Also, the foot pedal 7 being free, the counterweight 14 has pulled the lever 15 and its pitman 16 to forward or retracted position, whereby the

pitman head 89, engaged with the crank 87, has swung about the shaft 85 as a center and landed on the rest 92, the rotation of the shaft 85 meanwhile having disposed the arms 84 at their rearward swung position and having thereby, through the respective combination-links 80-81, moved the cross-head 74 and its attached wedges 75 to corresponding rearward position, so that the latter are thereby disengaged from the clasping arms 68.

Likewise, the elevated position of the beam 115 of the lifter F has disposed its carried yoke 120 immediately under the clasping arms 68 (notwithstanding that the carriage is at this time also in lifted position), so that the heel-rests 121 are disposed between the clasping arms 68 with the topmost part of the heel-rests 121 in horizontal alignment with the work-support d of the masking member D. The masking member D, it may here be said, has sufficient elastic or tensional bias for moreover swinging the clasping arms 68 to wide-apart or so-called heel-receptive position, as shown in Figures 4 and 7.

Here it may be said that the particular position of the glue transfer or printing roll 124 relative to the carriage C is such that, when the carriage C is in its above-described lifted position, the plane of the work-support d is spaced substantially above the top of the printing roll 124, but with the reference point d' located rearwardly a suitable distance from, that is to say, approximately half of a radius of, the axis of the roll 124. It may be also pointed out that, notwithstanding the elevated position of the carriage C, the racks 130, pivoting about the pins 132 under bias of the springs 133, continue to have functional engagement with the respective gears 127.

The above description of the normal or initial position of the machine will best be understood by an examination of Figures 1, 4, and 6.

Proceeding now to a description of the use of the machine of my invention, as a first step the operator mounts the heel H in inverted position in the machine by placing the rear edge f of the heel on the reference point d' of the work-support d; next the operator places the heel side edges e, g, on the respective heel-rests 121, and then steps on the foot pedal 7. The downward stroke of the pedal 7 effects a rearward stroke of the pitman 16, but since the carriage C, being blocked by the dogs 54, cannot for the moment be moved, the pitman 16 rotates the shaft 85 through the crank 87, meanwhile departing from the rest 92; the rotation of the shaft 85 swings the arms 84, 84', forwardly, whereby, through the respective composite links 80-81, the cross-head 74 and its carried wedges 75 are shifted also forwardly until the wedges 75 are engaged with the respective clasping arms 68. Continued forward movement of the wedges 75 then causes the arms 68 to swing or approach one toward the other, the ends 70 thereof likewise shifting the heel-rests 121, which pass under the respective heel edges e, g, thereby lifting the same into horizontal alignment with the groove 73. Upon further movement of the wedges 75, the arms 68 function to cause the member D to engage upon and fully embrace the heel arc e, f, g, so that, as the masking rib d passes under the heel edges e, f, g, the peripheral margin of the heel cup a is masked a predetermined distance, as c, defined by the width of the upper face of the masking member d, that is to say, the lower wall of the groove 73. Meanwhile, the heel-edge e, f, g, is engaged between the V-shaped walls of the groove 73.

whereby the heel H is locked in place and supported securely on, and for movement with, the carriage C.

The heel H having been thus locked, as it may be said, on the carriage C, the springs 82 yield for permitting elongation of the respective composite links 80-81 as the rotation of the shaft 85 swings the arms 84, 84', toward their respective forward positions. Meanwhile, the latch 94 yields to engagement by the end of the adjacent link-part 81 that is attached to the arm 84 until, when the latter has swung the part 81 upwardly sufficiently for the purpose, the latch 94 slips under the part 81 and latches the same and the crank-shaft 85 in completely rotated final position, whereby the arms 68 are tensionally biased upon the heel H, as best seen in Figure 2.

As the shaft 85 approaches its said final position, the end of the adjacent link-part 81 that is attached to the arm 84' engages the toe 104 and swings the lever 102, and thus, in turn, through the rod 105, trips the latch lever 107 for releasing the detent 111 from the carriage lifter F, thereby permitting the carriage C to drop from its lifted position; in so doing, the carriage C tilts or pivots on the front rollers 62 as the rear rollers 65 descend through the slots 46 onto the floor of the respective ways 41; meanwhile, the pins 118, working in the grooves 119, permit the heel-rest lifter F to descend by gravity until the beam 115 rests on the stops 116, whereby the heel-rests 121 are substantially lowered below the tangential plane of the roller 124, all as best seen in Figures 7 and 8.

As the carriage C tilts to its lowered position, the arm-ends 10, the anchor 72, and the curved masking member D all sink into the elastic body of the roll 124, while between these several members the roll 124 protrudes upwardly into flattened engagement with more or less of the concave surface of the closed end of the heel cup a. As will presently more fully appear, the periphery of the roll 124 is covered with a film of glue, and the glue which is on that portion of the periphery of the roll 124 which comes into contact with the heel-cup a, is adherently transferred thereto from the roll 124.

It will be observed that up to this time the horizontal motion of the carriage C has been delayed, due to the concurrent lost motion between the carriage and the pitman 16 occasioned by the rotation of the shaft 85. But when the shaft 85 is locked in final rotated position on the carriage C, Figure 2, the latter, guided in the ways 41 and impelled by the pitman 16, now commences its movement toward the rear of the machine. In so doing, the racks 130 revolve the gears 127, which, in turn, through the pawls 128 and ratchet wheels 126, rotate the shaft 112 and likewise the transfer-roll 124, which latter, it may here be said, has by this means, a peripheral speed substantially equal to the rearward velocity of the carriage C and its supported heel H. As the roll 124 is thus revolved, additional glue-covered periphery of the roll 124 is presented to the surface of the heel-cup a, and at the same time the rearward translation of the heel H relative to the axis of the roll 124 presents additional heel-cup surface to the roll 124, whereby the central portion of the heel-cup a is printed, as may be said, with a film of glue b. This glue-transferring operation is accomplished during the approximately first half of the rearward stroke of the carriage C. The revolution of the roll 124 continues, however, until the carriage C arrives at the end of its rear-

ward stroke, whereby the roll 124 is caused to again present a glue-carrying surface on its upper side in preparation for the next heel-gluing cycle of operation of the machine.

During this glue-printing operation, however, the masking member D prevents the contact of the roll 124 with the edge e, f, g, and margin c of the heel-cup a. Such portions of the heel-cup a, therefore, remain free of glue, in accordance with my invention. Likewise, and in further accordance with my invention, the film of glue b, so transferred or printed on the heel-cup a, is of uniform thickness, which is accomplished as follows,

As the transfer roll 124 is revolved, the feeder roll 138 and wiper roll 152 are driven in unison with the roll 124 through the respective gear-trains 134-135 and 139-140. The under side of the feeder roll 138 is immersed in the body of glue 33, a portion of which attaches itself to the roll 138. The rotation of the roll 138 is from its under side toward the wiper roll 141. The wiper roll 152 is driven in the opposite direction to the roll 138 and is spaced therefrom a suitable distance (too small to be observed in the drawings). The resulting wiping action is to allow merely a predetermined but uniform thickness or film of glue to remain on the upper side of the roll 138. The excess glue removed by the wiper roll 152 is returned to the glue body 33. The feeder roll 138 and transfer roll 124 are driven at the same peripheral speed, and since they are tangentially engaged, the film of glue on the roll 138 is transferred to the periphery of the roll 124 and thence to the heel-cup a with the same uniformity and thickness as determined by the setting of the wiper roll 152.

As the carriage C continues its rearward movement, the rear rollers 65 pass under the respective dogs 49, which swing up freely to permit the rollers 65 to pass and then drop down again, for purposes presently more fully appearing. The stationary stop 38 is so positioned on the rail 35 as to engage the latch-head 94 as the carriage C approaches the end of its rearward movement and as a result of the latch-head is held back as the carriage C moves to the final limit of its rearward travel. As will be seen by reference to Figure 2, this has the effect of unlatching the link-part 81 that is attached to the arm 84. Because the foot pedal 7 is at such moment still being depressed, the pitman 16 will still be urged rearwardly and the arm 84, together with the associated links 81, will still be held upwardly in the position in which they were then latched, with the result that the heel H will still be clamped in place.

As the operator undertakes to release the pedal 7, however, the heel H is manually grasped and held so that it can be lifted out of the machine immediately upon being released. Thereupon, when the operator releases the pedal 7, the pitman 16 begins to return to its initial position under the impulse of the counter-weight 14. During the initial stage of this return movement, however, the arms 84, being unlatched, will swing downwardly and the associated links will shift longitudinally rearwardly under the influence of the springs 82, thereby introducing at the beginning of the return stroke an initial amount of lost motion between the pitman 16 and the carriage C, the return movement of the latter being delayed while the pitman 16 concurrently rotates the shaft 85 to its initial position relatively to the carriage C. This motion, through the links 80, 81, and cross-head 74, releases the wedges 75

from the clasping arms 68, which are, in turn, under elastic bias of the member D, released from the heel H and shifted apart, thus permitting the operator to remove the heel H from the machine.

When the crank 85 has resumed its initial position on the carriage C, the pitman 16 acts to shift the carriage C forwardly. During the initial stage of the return movement of the carriage C, the rollers 65 ride up on the dogs 49 and the rearward end of the carriage C is elevated to initial position. As the rollers come up, they strike the under side of the dogs 54, which swing freely upwardly, and then drop down behind the rollers 65 into initial stop-forming position as the carriage C reaches the end of its return stroke.

The co-operation of the several instrumentalities hereinbefore described impart, as will be seen, a defined path of motion to the carriage C. It being borne in mind that the heel H is supported on the carriage C so as to position the concave closed end of the heel-cup a in registration with the convex periphery of the roller 124, the motion of the carriage C is then such as to, in the first instance, tilt the carriage from its elevated initial position to a lowered position so as to bring the closed end of the cup a into glue-printing engagement with the stationary roller 124, then to rollably engage the open end of the cup a upon the roller 124, and finally to return the carriage to its initial position in an elevated path disposed substantially above the tangential plane of the roller 124, in such manner as to wholly avoid any wiping or sliding engagement of the carriage and its supported work with the roller.

It will be seen that my invention accomplishes its intended purposes, and it will be understood that changes and modifications may be made in the details of form, construction, arrangement, and combination of parts hereinbefore described without departing from the nature of my invention and the scope of the appended claims.

Having thus described my invention, what I claim and desire to secure by Letters Patent is,

1. In a heel-gluing machine, in combination, a glue-transfer roller, and heel-supporting means including a carriage tiltable from raised to lowered position in the plane of the roller for engaging the same with a supported heel.

2. In a heel-gluing machine, in combination, a glue-transfer roller, heel-supporting means including a carriage tiltable from raised to lowered position in the plane of the roller for engaging the same with a supported heel, and means for latching the carriage in raised position.

3. In a heel-gluing machine, in combination, a glue-transfer roller, a carriage tiltable from elevated to lowered position in the plane of the roller, heel-clasping members actuatable for supporting a heel on the carriage, means for normally latching the carriage in elevated position, and means responsive to heel-clasping actuation of said members for unlatching the carriage from elevated position.

4. In a heel-gluing machine, in combination, a glue-transfer roller, a carriage tiltable from elevated to lowered position in the plane of the roller, said carriage being adapted when in such lowered position to slide rearwardly, heel-clasping members actuatable for securing a heel on the carriage, means for normally latching the carriage in elevated position, actuating means for said clasping members including a crank swingable upwardly and forwardly on the carriage, means for latching the crank in such

upwardly and forwardly swung position, stationary stop-means for engaging the crank-latching means during swing of the crank for unlatching the carriage, means responsive to movement of the carriage and thereby unlatching the crank, and means for restoring the carriage to elevated latched position.

5. In a heel-gluing machine, the combination, with a shiftable carriage, of clasping arms actuatable for engaging a heel on the carriage, reciprocable actuating means for motivating the carriage, and a lost motion device between the actuating means and the carriage operable for concurrently engaging said arms on a heel while delaying motion of the carriage during initiation of the stroke of the actuating means, and for concurrently releasing said arms from the heel while delaying motion of the carriage at the termination of the stroke of the actuating means.

10 6. In a heel-gluing machine, the combination,

with a shiftable carriage, of clasping arms actuatable for engaging a heel on the carriage, reciprocable actuating means for motivating the carriage, and a lost motion device between the actuating means and the carriage operable for concurrently engaging said arms on a heel while delaying motion of the carriage during initiation of the stroke of the actuating means, and for concurrently releasing said arms from the heel while delaying motion of the carriage at the termination of the stroke of the actuating means, said lost motion device including means for restraining motion of the carriage pending engagement of said arms on the heel.

35 7. In a heel-gluing machine, in combination, a glue-transfer roller, a tiltable carriage shiftable alternately in respective raised and lowered positions, means responsive to movement of the carriage in raised position for latching the same in said position, means including heel-clasping members actuatable for supporting a heel on the carriage, means responsive to actuation of said clasping members for latching said members in heel-clasping position, means also responsive to actuation of said members for unlatching the carriage from raised position, said glue-transfer roller being adapted for engaging said heel when the carriage is shifted in lowered position, means responsive to terminal movement of the carriage in lowered position for unlatching said clasping members, and means responsive to initial movement of the carriage in alternate direction for lifting the same to raised position.

8. In a machine for applying glue to the concave surface of the cup of a heel, in combination, a glue-transfer roller, a reciprocable carriage tiltable from elevated to lowered position in the plane of the roller, means for positioning a heel on the elevated carriage with the concavity of the heel-cup in registration with the convex surface of the roller, means for tilting the carriage to lowered position for engaging the closed end of the heel with the roller, and means for moving said carriage in lowered position for effecting rolling engagement of the open end of said heel with the roller.

9. In a heel-gluing machine, in combination, means for applying glue to the cup of a heel, reciprocable means including a member movable for positioning the heel with respect to the glue-applying means, said member having a groove for receiving the arc of said heel, means for guiding the arc of the heel into said groove responsive to heel-positioning movement of said member, and means responsive to movement of

the carriage for removing said guiding means from the path of the carriage.

10. In a heel-gluing machine, in combination, means for masking the peripheral portion of the cup of a heel, gluing means, and means for shifting the masked heel crosswise over the gluing means for applying a film of glue to an exposed portion of the cup of the heel.

11. In a heel-gluing machine, in combination, means for gripping a heel at its periphery and concurrently masking the marginal portion of the cup of the heel, gluing means, and means for shifting the gripped and masked heel crosswise over the gluing means for applying a film of glue to an exposed portion of the cup of the heel.

12. In a heel-gluing machine, in combination, means including a cushion-member for gripping a heel at the periphery thereof and concurrently by said cushion-member masking the marginal portion of the cup of the heel, gluing means, and means for shifting the gripped and masked heel crosswise over the gluing means for applying a film of glue to an exposed portion of the cup of the heel.

13. In a heel-gluing machine, in combination, means including a cushion-member having a groove in its inner face for gripping a heel at its periphery and concurrently disposing the cushion-member in heel engagement at its said groove for masking the marginal portion of the cup of the heel, and means for applying a film of glue to an exposed portion of the cup of the heel.

14. In a heel-gluing machine, in combination, means including a cushion-member for supportingly engaging a shoe heel at a point upon its periphery opposite its breast and having extensions for engaging the periphery of the heel intermediate its breast and said point of support-engagement, means for engaging said cushion-member-extensions with the heel for masking the peripheral portion of the cup thereof, and means for applying a film of glue to an exposed portion of the cup of the heel.

15. In a heel-gluing machine, in combination, means including a cushion-member for supportingly engaging a shoe heel at a point upon its periphery opposite its breast and having extensions for engaging the periphery of the heel intermediate its breast and said point of support-engagement, means including a pair of swingable companion arms for engaging said cushion-member-extensions with the heel for masking the peripheral portion of the cup thereof, and means for applying a film of glue to an exposed portion of the cup of the heel.

16. In a heel-gluing machine, in combination, means including a cushion-member for supportingly engaging a shoe heel at a point upon its periphery opposite its breast and having extensions for engaging the periphery of the heel intermediate its breast and said point of support-engagement, means including a pair of pivotally swingable companion arms and shiftable wedge members for swinging the arms with the cushion-member-extensions attached thereto for engaging with the heel for masking the peripheral portion of the cup thereof, and means for applying a film of glue to an exposed portion of the cup of the heel.

17. In a heel-gluing machine, in combination, front and rear rests for supporting a heel in an inverted position with its cup presented downwardly, the rear rest being swingable and the

front rest engaging the heel at a point on its periphery opposite its breast and comprising a cushion-member having extensions for engaging the periphery of the heel intermediate its breast and said point of support, means including pivotally actuatable arms for engaging the cushion-member-extensions with the heel for masking the peripheral portion of the cup thereof, means for swinging the rear rest out of engagement with the heel when said cushion-member is in cup-masking position, and means for applying a film of glue to an exposed portion of the cup of the heel following swinging of said rear rest.

18. In a heel-gluing machine, in combination, glue-applying means, means for masking the peripheral portion of the cup of a heel, said masking means including a carriage for supporting the heel over said glue-applying means, and means for actuating the carriage crosswise over the glue-applying means for engaging the masked heel with the glue-applying means.

19. In a heel-gluing machine, in combination, means including a glue-applying roll, means for masking the peripheral portion of the cup of a heel, said masking means including a carriage for supporting the heel over said roll, and means for actuating the carriage for engaging the masked heel with the roll and for shifting the heel while in engagement with the roll for application of glue to the exposed portion of its cup.

20. In a heel-gluing machine, in combination, means including a glue-applying roll, means for masking the peripheral portion of the cup of a heel, said masking means including a carriage for supporting the heel for movement over and relatively to the roll, and means for actuating the carriage for first engaging the heel at the arc of its cup with the roll and then shifting the heel relatively to the roll for application of glue to an exposed portion of the cup of the heel.

21. In a heel-gluing machine, in combination, means including a glue-applying roll, a shiftable carriage, means mounted on and movable with the carriage for both removably securing the heel to the carriage and for masking the marginal portion of its cup, means for actuating the carriage for first engaging the heel at the arc of its cup with the roll and then shifting the heel relatively to the roll for application of glue to an exposed portion of the cup of the heel, and means for releasing said securing means for removal of the heel.

22. In a heel-gluing machine, in combination, means including a cushion-member for engaging respective shoe-heels of different sizes at a point upon its periphery opposite the breast and having extensions for engaging the periphery of the heel intermediate its breast and said point of support, means including companion arms for yieldingly engaging said cushion-member-extensions with the selected heel for masking the peripheral portion of the cup thereof, means for yieldingly actuating the arms into masking position, and means for applying a film of glue to an exposed portion of the cup of the particular heel.

23. In a heel-gluing machine, in combination, means including a cushion-member for engaging a shoe-heel at a point upon its periphery opposite the breast and having extensions for engaging the periphery of the heel intermediate its breast and said point of support, means including companion swingable arms for yieldingly engaging said cushion-member-extensions with the heel for masking the peripheral portion of the cup thereof, means for yieldingly actuating the arms

into masking position, means for latching said arms in heel masking engagement, and means for applying a film of glue to the cup of the engaged heel.

24. In a machine for applying glue to the concave face of the cup of a heel, in combination, a glue-transfer member having a convex surface, means for positioning a heel with the concavity of the heel-cup in registration with the convex surface of the transfer member, and means for shifting the heel-cup relatively to the transfer member.

25. In a heel-gluing machine, in combination, a glue-transfer roller, a reciprocable carriage, means for securing a heel in inverted position on

the carriage, and means for swinging the carriage for first engaging the heel at its cup with the roller and then shifting the heel relatively to, and with its cup in engagement with, the roller.

26. In a heel-gluing machine, in combination, a glue-transfer roller, a reciprocable carriage, means for securing a heel in inverted position on the carriage, means for swinging the carriage for first engaging the heel at its cup with the roller and then shifting the heel relatively to, and with its cup in engagement with, the roller, and means for revolving the roller in synchronism with movement of the carriage.

WALTER A. THUM.
